Attorney.

UNITED STATES PATENT OFFICE.

CHRISTIAN A. R. L. VER GENIUS, OF GALESBURG, ILLINOIS, ASSIGNOR OF ONE-HALF TO GUSTAVE A. VER GENIUS, OF SAME PLACE.

PRINTER'S QUOIN.

SPECIFICATION forming part of Letters Patent No. 298,639, dated May 13, 1884.

Application filed July 23, 1883. (No model.)

To all whom it may concern:

Be it known that I, CHRISTIAN A. R. L. VER GENIUS, a citizen of the United States, residing at Galesburg, in the county of Knox and State of Illinois, have invented certain new and useful Improvements in Printers' Quoins; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to printers' quoins; and it consists in constructions and combinations hereinafter described.

In the accompanying drawings, which illustrate my invention and its application in use, 20 Figure 1 is a top plan of a portion of an ordinary printer's chase, matter to be locked therein, and my improved quoin. Fig. 2 is a side elevation of the quoin and part of a chase. Fig. 3 shows sectional elevations transverse 25 and lengthwise of the quoin.

Referring to the drawings by letters, the same letter indicating the same part in the different figures, A represents an ordinary printer's chase; B, ordinary columns of type or 30 other matter, and C the strips which are placed next the type, and known generally as "furniture," or head-sticks; side-sticks, and foot-sticks.

D represents my improved quoin, consisting of blocks D', each with a horizontal screw-threaded groove, d, in its face adjacent to its fellow-block. The blocks D' each have lugs e, which enter correspondingly-shaped recesses e' in the adjacent block when the two are 40 brought together, and thus properly align them for the reception of the conical screw-bolt G, which is placed horizontally in the quoin. A rubber band, h, also passes around the quoin in groove h' (shown in Fig. 3) to hold 45 the two blocks D' together when not in use.

The bolt G is conical at its screw-threaded

end, and its outer end, g, is square or of other polygonal form in its cross-section. I is the head of a socket-wrench, one end of which fits upon the square end g of the bolt G, and the other end receives a handle, I', fitted loosely therein, so that it may be turned at an angle to the head I, as shown in the drawings. The handle I' is held in the socket I by a pin, i, which extends across and is secured in the hole 55 i' in the head I, and passes through a slot, i'', in the handle I.

In operation the quoin is placed, as usual, in the space between the chase and furniture. The end of the screw-bolt is then entered in 60 the quoin between the blocks D'. By forcing the screw-bolt forward by means of the wrench the blocks D' will be forced apart to lock the type firmly and securely in the chase. Any number of quoins may be used, and one wrench 65 used to operate all the screw-bolts. The flexure of the handle in the head I will permit of turning the handle I' at such angles with reference to the head I, as will permit of operating the wrench without its coming in contact 70 with the sides of the chase, as will be understood by reference to Fig. 2.

I am aware that printers' quoins have been formed of two blocks having vertical screw-threaded grooves in their adjacent faces, and 75 provided with a screw-bolt for forcing the blocks apart. My device differs from this form in that the grooves are horizontal, so that a longer groove and bolt can be used.

Having thus described my invention, what 80 I claim as new is—

A printer's quoin formed of blocks D' with horizontal screw-threaded grooves in their adjacent faces, in combination with a conical screw-threaded bolt, fitting and working in said horizontal groove, substantially as described.

In testimony whereof I affix my signature in presence of two witnesses.

CHRISTIAN A. R. L. VER GENIUS.
